COMBINED EGG HOLDER AND OPENER, CONDIMENT DISPENSERS AND HOLDER THEREFOR AND SPOON HOLDER

Frank D. O'Neill, 94 Willcocks St. W.,
Toronto, Ontario, Canada

Filed Feb. 10, 1970, Ser. No. 21,392

Term of patent 14 years

Int. Cl. D7—99

U.S. Cl. D44—24

FIG. 1

FIG. 2

FIG. 3

FIG. 5

FIG. 4

FIG. 6

FIG. 1 is a perspective view of a combined egg holder and opener, condiment dispensers and holder therefor and spoon holder showing my new design;

FIG. 2 is an end elevational view with the egg opener member omitted for ease of illustration;

FIG. 3 is a top plan view;

FIG. 4 is a sectional view on line 4—4 of FIG. 3;

FIG. 5 is a bottom plan view thereof; and

FIG. 6 is a sectional view taken on the plane of line 6—6 of FIG. 3; the egg cutter being removed.

I claim:

The ornamental design for a combined egg holder and opener, condiment dispensers and holder therefor and spoon holder, as shown and described.
